UNITED STATES PATENT OFFICE.

JAMES I. DEPEW, OF LOUP CITY, NEBRASKA.

PLOWSHARE AND CULTIVATOR SHOVEL STRAIGHTENER.

Application filed March 28, 1927. Serial No. 179,025.

This invention relates to a device designed for use in straightening plow shares and cultivator shovels after they have been sharpened by the usual plow hammer.

5 The primary object of the invention is to provide a form on which the plow shares or cultivator shovels may be positioned and hammered into shape, should they be twisted or otherwise bent from their normal configurations.

10 A further object of the invention is to provide a device having enlargements formed on the upper surface thereof, which enlargements conform to the shapes of the shares or blades to insure the proper shaping thereof.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

25 Referring to the drawing:

Figure 1 is a plan view of a device constructed in accordance with the invention.

30 Figure 2 is a sectional view taken on line 2—2 of Figure 1.

Figure 3 is a sectional view taken on line 3—3 of Figure 1.

35 Figure 4 is a sectional view taken on line 4—4 of Figure 1.

Figure 5 is a sectional view taken on line 5—5 of Figure 1.

40 Referring to the drawing in detail, the device includes a solid member having an upper offset portion 5 and a laterally extended end portion 6, the end portions 6 conforming to the shape of the usual pointed end of a plow share.

45 The upper surface of the device curves upwardly from one edge thereof to a point substantially intermediate the side edges defining a substantially thick central portion and a curved upper surface conforming

50 to the shape of a plow share, the curved surface being indicated by the reference character 7.

At the forward end of the curved surface is a shoulder 8 that extends at an oblique angle with respect to the upper edge of the 55 curved surface 7 to the end that the flange of the usual plow share may rest thereagainst while it is being hammered into shape after sharpening.

55 A convex enlargement 9 is also provided on the upper surface and extends from the inner edge of the curved surface 7, to a point adjacent to the opposite edge of the device, the curvature of the enlargement 9 conforming to the concave curvature of the 60 usual cultivator share so that a cultivator shovel after it has been sharpened in the usual manner, may be positioned over the enlargement 9 and hammered to take the 65 shape of the enlargement, which is the true 70 cultivator shovel shape.

65 Extending from the upper edge of the laterally extended portion 6, is an enlargement 10 which has a thickened portion adjacent to the point where it merges into the 75 laterally extended portion 6, defining an inclined surface and a surface conforming to the usual shape of a lister share, to the end that the lister share may be positioned 80 thereover and hammered to properly shape 85 the lister share after it has been sharpened.

75 From the foregoing it will be seen that due to this construction, I have provided a form or a device to be used as an anvil on which plow shares or cultivator shovels may 80 be positioned and hammered to straighten or reshape them when they have become distorted, the reshaping usually being accomplished after the sharpening of the shares or cultivator shovels.

85 I claim:

90 1. In a device of the character described, a solid body portion, a laterally disposed end portion, said body portion having a curved surface extending from one edge of the body portion, a point substantially intermediate 95 the side edges of the body portion, a convex enlargement extending from the upper sur-

face of the body portion, and an enlargement extending in a direction opposite to the laterally disposed end portion.

2. In a device of the character described, 5 a solid body portion having an elongated concaved upper surface and having a convexed surface adjacent thereto, one edge of the body portion being curved laterally de-

fining a pointed extremity, and an enlargement extending from the opposite side edge 10 of the body portion.

In testimony that I claim the foregoing as my own, I have hereto affixed my signature.

JAMES I. DEPEW.
